ABSTRACT OF THE DISCLOSURE

An asymmetric groove and land profile for cooperating female and male rotors in a screw rotor compressor or expander. One flank of a female rotor groove is disposed generally inside and the other flank generally outside a circular arc having its centre at the point of intersection between the pitch circle and a radial line through the innermost point of the groove, resulting in a small blow hole, negligible pockets, unidirectional thrusts on both rotors, and a large displacement volume for the size of the particular apparatus.

The present invention relates to a pair of rotors for and to a screw rotor machine for compression or expansion of an elastic working fluid.

A screw rotor machine comprises generally a casing provided with a working space having high pressure and low pressure ports and including at least two intersecting bores with parallel axes, and cooperating rotors of male and female type provided with helical lands and intervening grooves with a wrap angle of less than 360° which rotors are disposed in the bores of the working space. A male rotor is a rotor in which each land and groove has at least its major portion located outside the pitch circle of the rotor and has two generally convex flanks located outside the pitch circle, while a female rotor is a rotor in which each land and groove has at least its major portion located inside the pitch circle of the rotor and has two generally concave flanks located inside the pitch circle of the rotor.

When the rotors rotate a land of one rotor enters a groove of the cooperating rotor and vice versa. In this way, chevron shaped chambers limited by the flanks of the grooves and by the walls of the working space are formed. Each of said chevron shaped chambers comprises a portion of a male rotor groove and a portion of a female rotor groove communicating therewith which female rotor groove when seen in the direction from the apex of the chamber is located on the nearest side of the female rotor land entering the male rotor groove of the chamber. Each such chevron shaped chamber has its base end located in a stationary plane transverse to the axes of the rotors and disposed adjacent to the high pressure port, which plane is common for all chevron shaped chambers, and has its apex located at the intermesh between a land of the male rotor and a groove of the female rotor. When the rotors rotate the apex of the chevron shaped chamber is in this way moved axially in relation to the stationary transverse plane so that the volume of the chamber varies. Each groove portion forming a leg of such a chamber has a first flank, forming the peripherally outer wall of said leg, and a second flank, forming the peripherally inner wall thereof.

The form of the portion of the chevron shaped chamber located at the apex thereof is dependent on the form of the flank profile of the rotor lands and grooves. Several different types of flank profiles for the female rotor

2

grooves and the male rotor lands cooperating therewith are known which flank profiles give the machine different characteristics.

A first flank profile, the point-generated one, which is shown for instance in U.S. Patent 2,473,233, is formed in such a way that the outline of each female rotor groove flank in a plane transverse to the axis of the rotor follows an epicycloidal curve generated by the radially outermost point of the outline of the cooperating male rotor land flank, while the outline of the cooperating male rotor land flank follows an epicycloidal curve generated by the radially outermost point of the outline of the cooperating female rotor groove flank. In a screw rotor machine provided with rotors having symmetrically point-generated flanks where the flanks of a male rotor land meet each other in one point and where the female rotor is not provided with any addendum located outside the pitch circle, the sealing lines between the tips of the lands of the male and female rotors, respectively, and the barrel walls of the working space meet the intersection line between the bores of the working space located at the apex of the chevron shaped chamber in one and the same point so that the different chevron shaped chambers are completely sealed in relation to each other. From this point, sealing is obtained between the flanks of the rotors along a line which follows the helical tip of the male rotor land in the direction from the stationary transverse plane in which the base ends of the chevron shaped chamber are located to the point where the tip of the male rotor land hits a point on the second female rotor groove flank located at the pitch circle. From this point the sealing line follows the helical edge of the second female rotor groove flank in the direction towards the stationary transverse plane in which the base ends of the chevron shaped chambers are located until that this edge hits the radially innermost point of the cooperating male rotor land.

In this way a pocket-formed extension of the chevron shaped chamber is formed on the other side of the transverse plane in which the tips of the outer groove flanks hit each other. Owing to the form of this pocket the area of the second female rotor groove flank facing the chevron shaped chamber is larger than the corresponding area of the first female rotor groove flank. In this way the female rotor is worked upon by the working fluid with a torque which tries to revolve the female rotor in the direction towards decreasing volume of the chevron shaped chamber, i.e. the female rotor gets a negative torque. On the axially opposite side of the intermesh between the rotors a corresponding pocket is formed which communicates with the low pressure port which pocket has its apex located at the first female rotor groove flank and extends all the way to the transverse plane through the point in the chevron shaped chamber in which the edge of the flank of the female rotor groove hits the tip of the male rotor land so that said pockets overlap each other axially.

Another flank profile, the circular one, which is shown for instance in U.S. Patent 2,622,787, is formed in such a way that the outline of each female rotor groove flank in a plane transverse to the axis of the rotor follows a circular arc having its centre on the pitch circle of the rotor, and the outline of the cooperating male rotor land flank comprises a crest portion which follows a circular arc having its centre on the pitch circle of the rotor and a root portion which follows an epicycloidal curve generated by the radially outermost point of the outline of the circular female rotor groove flank. In a screw rotor machine provided with rotors having symmetrically circular flanks where those of the male rotor meet each other in one point and where the female rotor

is not provided with any addendum located outside the pitch circle, the sealing line between the edge of the second female rotor groove flank and the barrel wall of the working space hits the intersection line between the bores of the working space in a point which is more distant from the stationary transverse plane in which the base ends of the chevron shaped chamber are located than the point in which the sealing line between the cooperating male rotor land tip and the barrel wall of the working space hits said line, for which reason the sealing line will not be continuous at the apex of the chevron shaped chamber. This discontinuation causes a blow hole having a certain but limited area which blow hole forms a communication between the chevron shaped chamber and the adjacent chevron shaped chamber in the direction from the stationary transverse plane. The helical edge of the first female rotor groove flank hits after passing said point of the intersection line between the bores the flank of a male rotor land which limits said adjacent chevron shaped chamber in a point located at the crossing point between the circular crest portion and the point generated root portion thereof. From this point, which is the end of said blow hole, the sealing line between the rotors follows a line around the circular crest portion of the male rotor land located in a transverse plane, to the point where the flank of the male rotor land limiting the adjacent chevron shaped chamber at the crossing between the circular crest portion of the land and the point generated root portion thereof hits the edge of the second female rotor groove flank. From this point the sealing line then follows the helical edge of the second female rotor groove flank in the direction towards the stationary transverse plane to the point where said flank edge hits the radially innermost point of the male rotor land. Owing to the fact that the sealing line from one edge of the female rotor groove to the other edge thereof is located in a transverse plane the areas of the first and second female rotor groove flanks facing the chevron shaped chamber will be of the same size so that the female rotor theoretically will not be worked upon by any torque from the working fluid. The portions of the rotor grooves located on the axially opposite side of the intermesh between the rotors are in communication with the low pressure port but without any axial overlap of the type which is to be found in connection with the pockets formed with the point-generated flanks.

A third flank profile, the travelling generated one, which is shown for instance in U.S. Patent 3,245,612, is formed in such a way that the outline of each female rotor groove flank in a plane transverse to the axis of the rotor follows a curve defined by a radius vector swung from the point in which the pitch circle intersects with a radial line drawn from the centre of the rotor through the radially innermost point of said flank outline, the length of which radius vector increases continuously as the vector is swung from the radially innermost point of the flank outline to the point thereof located at the pitch circle and that the outline of the cooperating male rotor land flank follows a curve generated by the female rotor groove flank and forming the envelope to the outline of the flank of the female rotor groove. In a screw rotor machine comprising rotors having symmetrically travelling generated flanks where the flanks of the male rotor land meet each other in one point and where the female rotor is not provided with any addendum located outside the pitch circle, the sealing line between the edge of the second female rotor groove flank and the barrel wall of the working space hits the intersection line between the bores of the working space in a point which is axially more distant from the stationary transverse plane in which the base ends of the chevron shaped chamber are located than the point in which the sealing line between the tip of the cooperating male rotor land

and the barrel wall of the working space hits said line for which reason the sealing line is not continuous at the apex of the chevron shaped chamber. This discontinuation causes a blow hole having an area the size of which is several times that of the corresponding blow hole of the circular profile which blow hole forms the communication between the chevron shaped chamber and the adjacent chevron shaped chamber in the direction from the stationary transverse plane. The helical edge of the second female rotor groove flank, sealing against the barrel wall of the working space hits after passing said point on the intersection line between the bores of the flank of the male rotor land which limits said adjacent chevron shaped chamber in a point located at the pitch circle of the male rotor, i.e. in the radially innermost point of said flank. From this point, which forms the end of said blow hole, the sealing line between the rotors then follows a generally S-shaped line which extends in the direction towards the stationary transverse plane from the radially innermost point of one flank of the male rotor land to the radially innermost point of the other flank of said land as well as from one flank edge of the female rotor groove to the other edge thereof so that both ends of the S-shaped line lie on the same axially directed line. Owing to the form of this S-shaped sealing line between the rotors the area of the second female rotor groove flank facing the chevron shaped chamber is smaller than the corresponding area of the first female rotor groove flank. In this way the female rotor is worked upon by the working fluid with a torque that tries to drive the female rotor in the direction towards increasing volume of the chevron shaped chamber, i.e. the female rotor has a positive torque.

For a certain dimension of the rotors and for a certain peripheral width of the radially outermost portion of the female rotor groove the point-generated profile gives the largest displacement volume, furthermore the point-generated profile has the advantage that no blow hole occurs between the different chevron shaped chambers. On the other hand the point-generated profile has the following disadvantages. The sealing line between the rotors at their intermesh will be relatively long which causes a relatively large leakage from the chevron shaped chamber directly to the low pressure side of the machine. Furthermore the radially outermost portions of the male rotor lands and of the female rotor lands will come into sealing proximity to each other which means that if the synchronisation between the rotors is not absolutely perfect there is a risk for direct contact between those two outer rotor land portions causing damage to both of them. Such damage causes leakage holes along the complete length of the cooperating land flank of the other rotor and results in leakage holes so large between the chevron shaped chamber and the low pressure side of the machine that the machine will be practically unusable. Owing to the fact that the female rotor as said above gets a negative torque, which means that the axial forces acting upon the male and female rotors are directed in opposite directions, in order to guarantee mechanical reliability such a machine must be provided with relatively large clearances between the rotors. In connection with the long sealing line at the intermesh between the rotors, mentioned above, this means that there will be a considerable leakage within the machine. A further disadvantage of the point-generated profile is the pocket-shaped extensions of the chevron shaped chambers mentioned above as when the transverse plane in which the edge of the first flank of the female rotor groove hits the tip of the land of the male rotor reaches the stationary plane through the base ends of the chevron shaped chambers a pocket is formed having no communication with the high pressure port which pocket, when the machine acts a compressor, cannot be emptied directly into the high pressure port owing to the fact that at the same time a channel

communicating with the low pressure port is formed at the first flank of the female rotor groove, which means that baffle means covering this low pressure channel must be inserted in the high pressure port. The volume of said high pressure pocket then decreases during compression of the working fluid enclosed therein down to zero volume. The pocket extends during the complete existence thereof all the way out to the edge of the second female rotor groove flange so that not only the torque acting upon the female rotor in the direction towards decreasing volume of the chevron shaped chamber increases but also a considerable bending torque acts upon the land of the female rotor which has broken under certain circumstances. The same is true, also when the machine acts as an expander, though the pocket at this time is exposed to vacuum instead of to overpressure. Furthermore, the tips of the lands of the female rotor are very wide in relation to the minimum thickness of the lands resulting in poor communication between the groove portions of a chevron shaped chamber.

For the same rotor dimensions and for the same peripheral width of the radially outermost portion of the female rotor groove, the circular profile gives a smaller displacement volume than that which is obtained with the point-generated profile. Furthermore, with the circular profile a blow hole is obtained, as mentioned above, between adjacent chevron shaped chambers. The sealing line between the rotors at their intermesh, however, will be considerably shorter than that of the point-generated profile so that the leakage from a chevron shaped chamber directly to the low pressure side of the machine will be smaller for this type of profile than for the point-generated profile. Furthermore the radially outermost portions of the male rotor lands and the female rotor lands are never in sealing proximity to each other so that the risk of serious damage to the rotors at direct contact therebetween will be considerably smaller and normally will be limited to point formed leakage holes in the intermesh. However, for damage to the radially outermost edges of the female rotor groove leakage holes will occur along the complete point-generated root portion of the male rotor flank. As said above the female rotor of the circular profile type will theoretically get no torque but owing to the dynamic forces from the working fluid there will be in practice pulsations around this zero torque so that the rotor will be worked upon alternatingly by a positive and a negative torque from the working fluid. In order to guarantee a constant direction of the torque and thus of the axial force acting upon the female rotor, the female rotor has been provided for this reason in practice with a certain addendum outside the pitch circle so that the female rotor will have a certain positive torque. As said above no pocket formed extensions of the chevron shaped chambers are formed with the circular profile so that the problem of draining such pockets is not present. However, the female rotor groove is closed, when the intermesh between the rotors reach the stationary transverse plane, momentarily along the complete transverse length of the flanks of the rotor groove which means that the working fluid enclosed in the female rotor groove in the last phase of the compression in a compressor gets a considerable acceleration and increase of pressure provided that the groove can not be completely drained in axial direction. A circular type of profile, however, is the type which up to now has been used in practically all screw compressors, at least when a screw compressor has been used to produce such a pressure increase that the machine really can be called a compressor and not a blower. Even though the tips of the lands of the female rotor are not so wide in relation to the minimum thickness of the lands the communication between the groove portion is not ideal which results in a re-expansion in a compressor and incomplete expansion in an expander.

For the same rotor dimensions and for the same peripheral width of the radially outermost portion of the

female rotor grooves the travelling generated profile gives a displacement volume which is somewhat smaller than that which is obtained with a circular profile. Furthermore the blow hole obtained at the travelling generated profile is several times larger than that obtained with the circular profile. The sealing line between the rotors at their intermesh, however, is considerably shorter than that of the circular profile so that the leakage from a chevron shaped chamber directly to the low pressure side of the machine is still smaller for this type of profile than for the circular one. In the same way as for the circular profile the radially outermost portions of the male rotor lands and the female rotor lands are never in sealing proximity to each other so that the damages occurring on the rotors from a possible direct contact therebetween will not be of any serious nature especially as no portion of the flanks of the lands generates more than one point of the cooperating flank so that the leakage holes which may occur only will be point formed and thus not cause any considerable leakage. As said above, the female rotor having a travelling generated profile gets a positive torque which means that the axial forces acting upon the cooperating rotors are directed in the same direction and that the risk for disturbance of the synchronization of the rotors are decreased so that it is possible to use a smaller clearance between the rotors for a travelling generated profile than the clearance which is necessary for a point-generated profile. As said above no pocket formed extensions of the chevron shaped chambers are obtained with the travelling generated profile so that the problem of draining such pockets is eliminated. Furthermore, the intermesh between the rotors does not lie within one single transverse plane so that the female rotor grooves are closed continuously as the contact point between the rotors reaches the stationary transverse plane. This means that the working fluid enclosed in the female rotor groove in the last phase of the compression does not get any fluid acceleration and pressure increase as is obtained with the circular profile so that the draining of the female rotor groove is considerably more uniform and calmer than that with the circular profile. The tips of the lands of the female rotor are the narrowest part of the lands and the communication between the different groove portions of a chevron shaped chamber are as ideal as possible.

U.S. Patent 2,174,522 suggests, on the other hand, combining the point generated profile and the circular profile in such a way that the first flank of the female rotor groove is provided with a point-generated profile and the second flank of the groove is provided with a circular profile. In this way a displacement volume is obtained which is smaller than that obtained with the symmetrically point-generated profile but larger than that obtained by the symmetrically circular profile. Furthermore no blow hole is obtained between adjacent chevron shaped chambers. The sealing line between the rotors at their intermesh is shorter than that of the symmetrically point-generated profile but longer than that of the symmetrically circular profile. However, the radially outermost portions of the male rotor lands and the female rotor lands will come into sealing proximity to each other which in combination with the fact that the female rotor gets a negative torque brings about a situation where serious damage may result to the rotors in the same way as for the symmetrically point-generated profile. In addition, pocket formed extensions of the chevron shaped chambers of the same type as those obtained with the symmetrically point-generated profile are obtained though those pockets have a considerably smaller volume. Owing to the fact that there is a circular profile this causes a momentary closing of the pocket along the complete second flank of the female rotor groove which pocket will in the last phase thereof extend all the way out to the outermost edge of the circular flank of the female rotor groove so that a considerable negative turning

torque of the female rotor is obtained and also a considerable bending torque of the land of the female rotor. The communication between the different groove portions of a chevron shaped chamber is worse than the symmetrically circular profile though not as bad as in a symmetrically point-generated profile, which means that the communication is considerably less than ideal.

Furthermore it has been suggested, as mentioned above in connection with the symmetrically circular profile, to provide the female rotor with addendums located outside the pitch circle of the rotor. These addendums give the female rotor a certain positive torque but this torque is of such a magnitude that for the dimensions of the addendum which is possible to use, the torque deriving therefrom can not balance even half the negative torque of the female rotor deriving from the symmetrically point-generated profile. Such addendums can thus not be used to give the combined point-generated and circular profile a positive torque. Furthermore addendums of this type produce blow holes for the point-generated profile and an increase of the blow hole area for the circular and the travelling generated profiles, respectively.

All known profiles have thus certain disadvantages which reduce the reliability and/or the efficiency of the machine in which it is included.

The aim of the present invention is to produce an optimum type of rotor profile for a screw rotor machine. The advantages for such a profile are unidirected axial forces on both rotors, resulting in a high mechanical reliability even with very small clearances between the flanks of the rotors which in turn results in high volumetric efficiency, a short sealing line between the flanks of the rotor also resulting in a high volumetric efficiency, a small blow hole area resulting in a high adiabatic efficiency, a large displacement volume resulting in smaller dimensions and lower mechanical and dynamic losses in relation to the mass of working fluid passing through the machine, an advantageous form of the trapped pocket resulting in a small total volume, a favorable discharge therefrom, practically no bending torque on the female rotor lands and negligible turning torque on the rotors, which means that the influence of the pocket can be disregarded, a favourable shape at least of the drive flanks of the machine, resulting in negligible sliding motion between cooperating points, which means driving by direct flank contact having practically tangentially directed contact forces, narrow tips of the female rotor lands in relation to the minimum thickness of said lands, resulting in a good communication between the different groove portions of a chevron shaped chamber, which means a higher adiabatic efficiency.

The invention will now be described more in detail in connection with the embodiments of compressors which are shown in the accompanying drawings.

FIG. 1 shows a longitudinal section along the line 1—1 in FIG. 3 through a compressor according to the invention.

FIG. 2 shows a longitudinal section along the line 2—2 in FIG. 4 through another compressor according to the invention.

FIG. 3 shows a cross-section along the line 3—3 in FIG. 1.

FIG. 4 shows a cross-section along the line 4—4 in FIG. 2.

FIGS. 5a—5d show on a larger scale a detail of FIG. 3 with the rotors in different angular positions.

FIG. 6 shows a fragmentary cross-section of a further type of rotors.

FIGS. 7a—7d show a detail of FIG. 6 with the rotors in different angular positions.

FIG. 8 shows in a diagram the volume of the trapped pocket as a function of the angular position of the male rotor.

In the compressor shown in FIGS. 1, 3 and 5a—5d a shaft 10 is driven from a source of power not shown. The

shaft 10 is rigidly connected with a male rotor 12 which is located in a casing 14 provided with a working space 16 comprising two parallel bores 18, 20 in the casing 14 which bores intersect along the lines 22 and 24. The male rotor 12 is located in the bore 18 while a female rotor 26 connected with the male rotor by a synchronizing gear 28 is located in the bore 20. The two rotors 12, 26 are mounted for rotation in the end walls 30, 32 of the casing 14. The working space 16 is provided with a low pressure port 34 and a high pressure port 36 communicating with low pressure and high pressure channels 38 and 40, respectively, in the casing for the gaseous working fluid.

The female rotor 26 is provided with six helical grooves 42 with a wrap angle of about 200° the major portions of which are located inside the pitch circle 44 of the rotor and with intervening lands 46 having a radial depth inside the pitch circle which is 18% of the outer diameter of the cooperating male rotor 12 and provided with addendums 48 located outside the pitch circle 44. Each groove 42 has two flanks 50, 52 provided with generally concave profiles.

The male rotor 12 is provided with four helical lands 54 having a wrap angle of about 300° the major portions of which are located outside the pitch circle 56 of the rotor and with intervening grooves 58. Each land 54 has two flanks 60, 62 provided with generally convex profiles.

The first flank 50 of the female rotor groove 42 is formed in such a way that in a plane transverse to the axis of the rotor from the bottom 64 of the groove to the pitch circle 44 the outline thereof follows an epicycloidal curve generated by the tip 66 of the cooperating male rotor land 54. The second flank 52 of the female rotor groove 42 is formed in such a way that in a plane transverse to the axis of the rotor the outline thereof is provided with an inner portion following a circular arc having its centre 68 outside the pitch circle 44 of the rotor and located on a radial line from the center 70 of the rotor drawn through the bottom 64 of the outline of the groove 42 and an outer portion out to the pitch circle 44 following a straight tangent to the circular arc of the inner portion, which means that the outline of the flank 52 is defined by a radius vector swung from the point of intersection 72 with the pitch circle 44 of a radial line drawn from the centre 70 of the rotor through the radially innermost point 64 of the flank outline, the length of which radius vector increases continuously as the vector is swung from the radially innermost point 64 of the flank 52 to the pitch circle 44. The flank 60 of the male rotor groove 58 is formed in such a way that in a plane transverse to the axis of the rotor from the tip 66 of the flank to the pitch circle 56 the outline thereof follows an epicycloidal curve generated by the point 74 located on the outline of the cooperating female rotor flank 50 at the pitch circle 44 of the female rotor. The flank 62 of the male rotor groove 58 is formed in such a way that in a plane transverse to the axis of the rotor the outline thereof follows a curve being the envelope of the outline of the cooperating female rotor groove flank 52.

As is well known to everybody skilled in the art of screw rotor machines the lands and grooves of the rotors provide together with the walls of the working space chevron shaped chambers, each comprising a portion of a male rotor groove and a portion of a female rotor groove communicating therewith. This female rotor groove, when seen in the direction from the apex of the chamber is located on the nearest side of the female rotor land entering the male rotor groove of the chamber. Each groove portion forming a leg of such a chevron shaped chamber is limited by a first groove flank forming the peripherally outer wall of the leg and a second flank forming the peripherally inner wall of the leg.

In the compressor shown in FIGS. 1, 3 and 5a—5d the first flank 50 of the female rotor groove 42 and the flank 62 of the male rotor groove 58 will form the outer walls of the chamber and the second flank 52 of the female

rotor groove and the flank 60 of the male rotor groove will form the inner walls of the chamber.

Owing to the fact that the flanks 50 and 60 are of the point-generated type there will thus be no blow hole forming a communication between adjacent chambers except for the small one deriving from the addendums 48 of the female rotor. However, as these flanks 50 and 60 are point-generated, pockets 76 and 78 will be formed, being of the known over pressure and suction type, respectively. Owing to the suction pocket 78 the axial portion of the high pressure port 36 must be provided with baffle means 80 covering the suction pocket 78. This baffle means 80, however, for certain angular positions of the rotors also covers the over pressure pocket 76, so that this pocket 76 can not be completely drained through the high pressure port 36. FIG. 5a shows the angular position of the rotors in which the pocket 76 is closed from the radial portion of the high pressure port 36, and the pocket 78 has its starting point, while FIG. 5b shows the angular position of the rotors in which the pocket 76 is brought out of communication with the axial portion of the high pressure port 36, and FIG. 5c shows the angular position of the rotors in which the pocket 76 is brought down to zero volume. FIG. 5d shows how the pocket 78 for a further revolution of the rotors is brought into communication also radially with the low pressure side of the compressor. As shown in FIGS. 5a-5c the contact point 82 between the flanks 52 and 62 travels continuously into the female rotor groove 42 as the rotors revolve thus reducing the volume of the pocket 76 and also which is still more important reducing the area of the second flank 52 of the female rotor groove 42 which is exposed to the pressure of the working fluid enclosed in the pocket 76. Owing to this travelling of the contact point 82 the working fluid enclosed in the pocket 76 will cause practically no bending torque at all on the female rotor land 46 in contrast to the conditions when the second flank of the female rotor groove is of the point-generated or of the circular type where the pressure pocket 76 extends all the way out to the pitch circle up to the moment when the volume thereof is brought down to zero volume.

In the diagram of FIG. 8 the variation of the volume V of the pocket 76 is shown by the curve A as a function of the angular position α of the male rotor where α is the angle shown in FIG. 5a. The angular positions of the rotors as shown in FIGS. 5a, 5b, 5c and 5d have been indicated by "a," "b," "c" and "d," respectively. In order to make a comparison with the symmetrically point-generated profile the curve B shows the variation of the volume of a corresponding pocket for that type of profile. The angular position "b" indicates the volume which is really trapped and which can never be drained to the high pressure port. As clearly shown in the diagram the trapped volume of the actual profile is only about 8% of the volume trapped in a compressor of the same dimensions provided with a symmetrically point-generated profile.

The compressor shown in FIGS. 2 and 4 differs from the one shown in FIGS. 1, 3 and 5a-5d by the following details. The compressor of FIGS. 2 and 4 is provided with means for introduction of a liquid into the working space comprising a distribution chamber 84 for liquid to which the liquid is admitted from a pressure liquid source not shown through an inlet opening 86, and a number of liquid injection channels 88 which connect the distribution chamber 84 with the working space 16. The compressor is not provided with any synchronizing gear but the rotors are connected to each other through direct flank contact. Furthermore the depth of the female rotor grooves inside the pitch circle is 20% of the outer diameter of the cooperating male rotor 12 and the outline of the second flank 90 of the female rotor groove 42 is in a plane transverse to the axis of the rotor formed as a circular arc having its centre outside the pitch circle 44 of the rotor and located on a radial line drawn from the centre of the

rotor through the radially innermost point of the outline of the flank 90. The outline of the flank 94 of the male rotor groove 58 follows then a curve being the envelope developed by the outline of the female rotor groove flank 90.

Furthermore small recesses 96 are provided in the high pressure end wall of the female rotor 26 at the bottom of each groove 42 thereof. These recesses 96 form during the complete closing of the pressure pockets a communication with the high pressure port 36 so that practically no working fluid will be trapped therein except for the very small volume enclosed in the recesses 96 which will be sluiced over to the low pressure side of the compressor and drained thereto.

In FIGS. 6 and 7a-7d a detail of a further modification of the rotor profiles is shown with the rotors in an angular position corresponding to those shown in FIG. 5c.

The depth of the grooves in the female rotor is about 19% of the outer diameter of the cooperating male rotor 12.

The minor bottom portion of the outlines of the female rotor flanks extending between the two points 98 and 100 is shaped as a circular arc having a radius "r" and its centre in the point of intersection 72 of the pitch circle 44 with a radial line drawn from the centre 70 of the rotor through the bottom point 64 of the outline of the groove 42. The circular arc extends symmetrically around said radial line over an angle β which is of the magnitude 20-30°. The radial extent of these minor portions of the flanks is thus only of the magnitude of 2.5-5% of the radial extent of the complete flank from the innermost point 64 to the pitch circle 44. The outline of the crest portion of the male rotor land 54 extending between the two points 102 and 104 is in a corresponding way shaped as a circular arc having its centre on the pitch circle 56 of the male rotor and extending over the same angle β . However, by means of recesses 106, 108 portions of the circular arc spaced from the limiting points 102, 104 of the arc are cut away leaving a low, narrow sealing strip 110 at the tip of the land 54. The substantial portion of the outline of the first flank 112 of the female rotor groove extending from the point 98 out to the pitch circle 44 is composed of a major section extending out to the point 114 and generated by the point 102 on the cooperating flank 116 of the male rotor groove 58 and a second extending from the point 114 to the pitch circle 44 and following a straight line drawn from the pitch circle, through point 114 and passing through the centre 70 of the rotor. The radial extent of this minor section is about 15% of the radial extent of the complete flank. The substantial portion of the outline of the second flank 118 of the female rotor groove extending from the point 100 to the pitch circle 44 is formed as a circular arc having a radius R with its centre located at point 120 outside the pitch circle 44 of the rotor on the straight line connecting the points 72 and 100 which point 120 corresponds to such a length of the radius R that the flank 118 in the point of intersection with the pitch circle 44 has a tangent passing through the centre 70 of the rotor. The substantial portion of the outline of the flank 116 of the male rotor groove 58 extending radially inside the point 102 is partly point-generated by the point 114 on the outer flank 112 of the female rotor groove and partly travelling generated by the minor section of said flank 112 located radially outside point 114. The substantial portion of the outline of the flank 122 of the male rotor groove extending radially inside the point 104 is travelling generated by the substantial portion of the second flank 118 of the female rotor groove 42 located radially outside the point 100. The point 114 on the outline of the first flank 112 of the female rotor groove 42 is located in the position where the straight line forming the outermost minor section of said flank outline at full intermesh between the female rotor groove 42 and the male rotor land 54 forms a tangent to the point-generated

part of the flank 116 of the male rotor groove 58 in the point being in contact with said point 114. In order to make it possible for the rotors to revolve in relation to each other, the section of the flank 112 extending outside the point 114 must not project inside said tangent in this point. In order to avoid point-generation of the section of the flank 116 of the rotor groove 58 adjacent to the pitch circle 56 which type of generation is undesirable with regard to the mechanical reliability, the angle γ (FIG. 6) between the tangent to the pitch circle 44 of the female rotor and the tangent to the first flank 112 of the female rotor groove 42 at the point of intersection between the pitch circle and the flank ought not to be larger than 90° . However, the smaller said angle γ is the larger will the area of the blow hole be. For these reasons it is desirable to make the angle γ as close to 90° as possible and this angle will be exactly 90° when the portion of the flank 112 adjacent to the pitch circle 44 is defined by a straight line through the centre 70 of the rotor. The reason for providing the female rotor groove with a circular bottom portion 98-100 and the male rotor land with a circular tip 102-104 provided with recesses 106, 108 is to form the sealing strip 110 which means that possible damage caused by a light contact between the tip of the male rotor land 54 and the barrel wall of the working space will not cause any considerable increase of the leakage hole from a chevron-shaped chamber to the low pressure side of the machine. However, the angular extent of those circular flank portions ought to be as small as possible in order not to increase the blow hole and not to reduce the displacement capacity of the machine.

The addendums 48 on the crests of the female rotor lands are shaped in such a way that the circumferentially outermost portions of the addendums reach the maximum diameter of the female rotor as soon as possible so that the increase of the blow hole derived from the addendum is as small as possible and partly so that the addendum can be provided with several recesses 124, 126 in order to bring about a sort of labyrinth seal between the crests of the female rotor lands and the barrel wall of the working space.

In order to guarantee mechanical reliability when the rotors are provided for direct flank contact therebetween, the flanks 116, 122 of a male rotor land 54 are shaped in such a way that there are clearing spaces between the flanks and the envelopes developed by the flanks 112, 118 of the female rotor 26, which spaces decrease in angular extent around the centre of the male rotor 12 to a minimum adjacent to the pitch circle 56 of the rotor at least on the flank 122 cooperating with the second flank 118 of the female rotor groove 42. In this way the following advantages are obtained. The flank portions of the different lands have in the point of contact practically the same peripheral speed which means substantially no pushing contact and thus no oscillations of the rotors derived therefrom. The risk of contact between the rotor tips when the flanks are produced by point-generation is avoided, resulting in the elimination of serious leakage holes from the chevron-shaped chambers to the low pressure side of the machine.

FIGS. 7a-7d correspond to FIGS. 5a-5d.

FIG. 7a shows that the angular position of the male rotor 12 in which the point 102 of the male rotor flank 116 cooperates with the point 114 of the female rotor flank 112 and the radial high pressure port is closed, corresponds to a larger value of the angle α than the angle corresponding to the closing of the radial high pressure port shown in FIG. 5a. As the contact point 82 on the second flank lies inside the pitch circle 44 at a distance from the pitch circle 44 somewhat exceeding the distance from point 114 on the first flank to the pitch circle 44, the flank portions of the pocket will produce a positive torque on the female rotor 26, and further the section

of the first flank 112 outside the point 114 will cause a positive torque on the female rotor 26.

From the angular position shown in FIG. 7a to the angular position shown in FIG. 7b the point 102 of the male rotor flank will move faster inwardly along the first flank of the female rotor groove than the contact point 82 will move inwardly along the second flank of the female rotor groove, this causing the fluid trapped in the female rotor groove to act upon the female rotor with a negative torque. However, the fluid acting upon the minor section of the first flank of the female rotor groove located outside the point 114 will act upon the female rotor with a positive torque, which torque is of about the same magnitude as the maximum negative torque obtainable in the pocket, so that the negative torque will be balanced all the time. Furthermore, the pocket will be in communication with the axial high pressure port, so that no additional pressure rise will be produced therein.

From the angular position shown in FIG. 7b to the angular position shown in FIG. 7c the point 102 of the male rotor flank will move slower inwardly along the first flank of the female rotor groove in relation to its distance to the centre of the female rotor than the contact point 82 will move inwardly along the second flank of the female rotor groove in relation to its distance from the centre of the female rotor, which means that the magnitude of the negative torque decreases continuously down to zero torque in the position shown in FIG. 7c. The working fluid positively trapped in the pocket will have a very small mass and will be enclosed in and discharged through the recesses 106, 108 so that no pressure rise occurs in the pocket. Since the pocket runs out to zero volume at the bottom of the female rotor groove the bending torque acting on the lands of the female rotor is negligible.

As shown in FIG. 7d the small mass of fluid trapped in the recesses 106, 108 is sluiced over to the low pressure side so that a special design for discharging this fluid is avoided.

The problems normally arising from a profile having the highly desirable feature of producing only a very small blow hole area is thus avoided so that all those problems are practically negligible.

The invention is of course not restricted to the embodiments shown but comprises everything falling within the scope of the following claims.

I claim:

1. A pair of cooperating rotors having helical lands and intervening grooves with a wrap angle of less than 360° and adapted for rotation around parallel axes within a working space of a screw rotor machine, said working space having high pressure and low pressure ports and including at least two intersecting bores, whereby a pair of communicating groove portions form a chevron-shaped chamber having its base end disposed in a plane transverse to the axes of the rotors and adjacent to the high pressure port of the machine, one of said rotors being of female rotor type, i.e. formed in such a way that at least the major portions of the lands and grooves are located inside the pitch circle of the rotor and that the flanks of the lands are generally concave, the other one of said rotors being of male rotor type, i.e. formed in such a way that at least the major portions of the lands and grooves are located outside the pitch circle of the rotor and that the flanks of the lands are generally convex, in which in a plane transverse to the axes of the rotors the outline defining a first flank of each female rotor groove, forming the peripherally outer wall of one leg of said chamber, has at least a substantial portion thereof inside and adjacent to the pitch circle of said rotor disposed completely inside a circular arc passing through the radially innermost point of said substantial portion and having its centre in the point in which the pitch circle intersects with a radial line drawn from the centre of the rotor through the radially innermost point of said flank outline, that

the outline defining the second flank of each female rotor groove, forming the peripherally inner wall of said leg of said chamber, has at least a substantial portion thereof inside and adjacent to the pitch circle of said rotor disposed so as to follow a curve defined by a radius vector swung from the point at which the pitch circle intersects with a radial line drawn from the centre of the rotor through the radially innermost point of said second flank outline, the length of said radius vector increasing continuously as the vector is swung from said radially innermost point of said substantial portion to said pitch circle, and that the outlines of the flanks of each male rotor land follow the envelopes developed by the female rotor flank outlines as the lands and grooves pass into and out of mesh.

2. A pair of rotors as defined in claim 1, in which each of said substantial portions of said female rotor groove flank outline has a radial extent being at least 75% of the radial extent of the complete flank outline from the pitch circle to the radially innermost point thereof.

3. A pair of rotors as defined in claim 2, in which said radial extent of each substantial portion is about 95% of said radial extent of the complete outline.

4. A pair of rotors as defined in claim 1, in which said substantial portion of said first flank outline of a female rotor groove includes a minor section immediately adjacent to the pitch circle of said rotor which minor section is disposed so as to follow a curve defined by a radius vector swung from the point at which the pitch circle intersects with a radial line drawn from the centre of the rotor through the radially innermost point of said first flank outline, the length of said radius vector increasing continuously as the vector is swung from the radially innermost point of said minor section to said pitch circle.

5. A pair of rotors as defined in claim 4, in which said minor section has a radial extent falling below 25% of the radial extent of the complete flank outline.

6. A pair of rotors as defined in claim 5, in which said radial extent of said minor section falls below 15% of the radial extent of the complete flank outline.

7. A pair of rotors as defined in claim 4, in which said minor section at the point of intersection with the pitch circle has a tangent extending therefrom to the centre of the rotor.

8. A pair of rotors as defined in claim 4, in which said minor section of said first female rotor groove flank outline at the radially innermost point thereof has a normal which passes through the point of intersection between the pitch circle and a radial line drawn from the centre of the rotor through the radially innermost point of said first flank outline.

9. A pair of rotors as defined in claim 8, in which said minor section follows a straight line drawn through the centre of the rotor.

10. A pair of rotors as defined in claim 1, in which the substantial portion of the first female rotor groove flank outline is disposed so as to follow an epicycloidal curve generated by the radially outermost point of the corresponding substantial portion of a male rotor land flank outline and said substantial portion of the male rotor land flank outline is disposed so as to follow an epicycloidal curve generated by the radially outermost point of said substantial portion of the female rotor groove flank outline.

11. A pair of rotors as defined in claim 4, in which the major section of the substantial portion of the first female rotor groove flank outline located radially inside said minor section thereof is disposed so as to follow an epicycloidal curve generated by the radially outermost point of the corresponding substantial portion of a male rotor land flank outline and the major section of said substantial portion of the male rotor land flank outline is disposed so as to follow an epicycloidal curve generated by the radially outermost point of said major section of said substantial portion of the female rotor flank outline.

12. A pair of rotors as defined in claim 1, in which said substantial portion of the second female rotor groove flank outline at the point of intersection thereof with the pitch circle has a tangent extending therefrom to the centre of the rotor.

13. A pair of rotors as defined in claim 1, in which said substantial portion of said second female rotor groove flank outline is disposed so as to follow a circular arc from the radially innermost point thereof to the point of intersection thereof with the pitch circle, with said arc having its centre located outside the pitch circle and on a straight line drawn from the radially innermost point of said substantial portion through the point of intersection between the pitch circle and a radial line drawn from the centre of the rotor through the radially innermost point of the complete outline of said second female rotor groove flank.

14. A pair of rotors as defined in claim 1, in which the first flank outline of a female rotor groove comprises a minor portion located adjacent to the radially innermost point of said flank outline which minor portion follows a circular arc having its centre located at the point in which the pitch circle intersects with a radial line drawn from the centre of the rotor through the radially innermost point of said first flank outline.

15. A pair of rotors as defined in claim 14, in which the second flank outline of a female rotor groove comprises a minor portion located adjacent to the radially innermost point thereof which minor portion follows a circular arc having its centre located at the point in which the pitch circle intersects with a radial line drawn from the centre of the rotor through the radially innermost point of said second flank outline.

16. A pair of rotors as defined in claim 15, in which said minor portions of the first and second flank outlines follow a common circular arc.

17. A pair of rotors as defined in claim 14, in which the minor flank portion of a male rotor land outline cooperating with said minor portion of the first flank outline of a female rotor groove is provided with a recess inside the envelope developed by the female rotor land outline, the edges of said recess being spaced from the limiting points of said minor portion of the male flank outline, and the second flank outline of the male rotor land outline is provided with a corresponding recess, whereby a sealing strip is provided at the crest of the male rotor land.

18. A pair of rotors as defined in claim 1, in which the female rotor lands are provided with addendums located outside the pitch circle of the female rotor and the male rotor grooves are provided with corresponding deden-dums inside the pitch circle of the male rotor.

19. A pair of rotors as defined in claim 1, in which there are clearing spaces between the flank outlines of the male rotor and the envelopes developed by the flank outlines of the female rotor, said spaces decreasing in angular extent around the centre of the male rotor to a minimum adjacent to the pitch circle of the rotor at least on the flank outline cooperating with the second flank outline of a female rotor groove.

20. A pair of rotors as defined in claim 1, in which the male rotor has four lands and grooves and the female rotor has six lands and grooves, with the radial extent of the grooves of the female rotor inside the pitch circle thereof being between 18% and 21% of the outer diameter of the male rotor.

21. A pair of rotors as defined in claim 20, in which the radial extent of the female rotor grooves inside the pitch circle is 18.5-20% of the outer diameter of the male rotor.

22. Screw rotor machine apparatus for selectively compressing and expanding an elastic working fluid and having a casing with a working space provided with spaced apart high pressure and low pressure ports and including at least two intersecting bores with coplanar axes, cooperating rotors disposed in said bores having helical

lands and intervening grooves with a wrap angle of less than 360° , whereby a pair of communicating groove portions form a chevron-shaped chamber having its base disposed in a plane transverse to the axes of the rotors and adjacent to the high pressure port of the machine, one of said rotors being of female rotor type, i.e. formed in such a way that at least the major portions of the lands and grooves are located inside the pitch circle of the rotor and that the flanks of the lands are generally concave, the other one of said rotors being of male rotor type, i.e. formed in such a way that at least the major portions of the lands and grooves are located outside the pitch circle of the rotor and that the flanks of the lands are generally convex, in which in a plane transverse to the axes of the rotors the outline defining a first flank of each female rotor groove, forming the peripherally outer wall of one leg of said chamber, has at least a substantial portion thereof inside and adjacent to the pitch circle of said rotor disposed completely inside a circular arc passing through the radially innermost point of said substantial portion and having its centre in the point in which the pitch circle intersects with a radial line drawn from the centre of the rotor through the radially innermost point of said flank outline, that the outline defining the second flank of each female rotor groove, forming the peripherally inner wall of said leg of said chamber, has at least a substantial portion thereof inside and adjacent to the pitch circle of said rotor disposed so as to follow a curve defined by a radius vector swung from the point at which the pitch circle intersects with a radial line drawn from the centre of the rotor through the radially innermost point of said second flank outline, the length of said radius vector increasing continuously as the vector is swung from said radially innermost point of said substantial portion to said pitch circle, and that the outlines of the flanks of each male rotor land follow the envelopes developed by the female rotor flank outlines as the lands and grooves pass into and out of mesh.

23. Apparatus as defined in claim 22, in which each of said substantial portions of said female rotor groove flank outline has a radial extent being at least 75% of the radial extent of the complete flank outline from the pitch circle to the radially innermost point thereof.

24. Apparatus as defined in claim 23, in which said radial extent of each substantial portion is about 95% of said radial extent of the complete outline.

25. Apparatus as defined in claim 22, in which said substantial portion of said first flank outline of a female rotor groove includes a minor section immediately adjacent to the pitch circle of said rotor which minor section is disposed so as to follow a curve defined by a radius vector swung from the point at which the pitch circle intersects with a radial line drawn from the centre of the rotor through the radially innermost point of said first flank outline, the length of said radius vector increasing continuously as the vector is swung from the radially innermost point of said minor section to said pitch circle.

26. Apparatus as defined in claim 25, in which said minor section has a radial extent falling below 25% of the radial extent of the complete flank outline.

27. Apparatus as defined in claim 26, in which said radial extent of said minor section falls below 15% of the radial extent of the complete flank outline.

28. Apparatus as defined in claim 25, in which said minor section at the point of intersection with the pitch circle has a tangent extending therefrom to the centre of the rotor.

29. Apparatus as defined in claim 25, in which said minor section of said first female rotor groove flank outline at the radially innermost point thereof has a normal which passes through the point of intersection between the pitch circle and a radial line drawn from the centre of the rotor through the radially innermost point of said first flank outline.

30. Apparatus as defined in claim 29, in which said

minor section follows a straight line drawn through the centre of the rotor.

31. Apparatus as defined in claim 22, in which the substantial portion of the first female rotor groove flank outline is disposed so as to follow an epicycloidal curve generated by the radially outermost point of the corresponding substantial portion of a male rotor land flank outline and said substantial portion of the male rotor land flank outline is disposed so as to follow an epicycloidal curve generated by the radially outermost point of said substantial portion of the female rotor groove flank outline.

32. Apparatus as defined in claim 25, in which the major section of the substantial portion of the first female rotor groove flank outline located radially inside said minor section thereof is disposed so as to follow an epicycloidal curve generated by the radially outermost point of the corresponding substantial portion of a male rotor land flank outline and the major section of said substantial portion of the male rotor land flank outline is disposed so as to follow an epicycloidal curve generated by the radially outermost point of said major section of said substantial portion of the female rotor flank outline.

33. Apparatus as defined in claim 22, in which said substantial portion of the second female rotor groove flank outline at the point of intersection thereof with the pitch circle has a tangent extending therefrom to the centre of the rotor.

34. Apparatus as defined in claim 22, in which said substantial portion of said second female rotor groove flank outline is disposed so as to follow a circular arc from the radially innermost point thereof to the point of intersection thereof with the pitch circle, with said arc having its centre located outside the pitch circle and on a straight line drawn from the radially innermost point of said substantial portion through the point of intersection between the pitch circle and a radial line drawn from the centre of the rotor through the radially innermost point of the complete outline of said second female rotor groove flank.

35. Apparatus as defined in claim 22, in which the first flank outline of a female rotor groove comprises a minor portion located adjacent to the radially innermost point of said flank outline which minor portion follows a circular arc having its centre located at the point in which the pitch circle intersects with a radial line drawn from the centre of the rotor through the radially innermost point of said first flank outline.

36. Apparatus as defined in claim 35, in which the second flank outline of a female rotor groove comprises a minor portion located adjacent to the radially innermost point thereof which minor portion follows a circular arc having its centre located at the point in which the pitch circle intersects with a radial line drawn from the centre of the rotor through the radially innermost point of said second flank outline.

37. Apparatus as defined in claim 36, in which said minor portions of the first and second flank outlines follow a common circular arc.

38. Apparatus as defined in claim 35, in which the minor flank portion of a male rotor land outline cooperating with said minor portion of the first flank outline of a female rotor groove is provided with a recess inside the envelope developed by the female rotor land outline, the edges of said recess being spaced from the limiting points of said minor portion of the male flank outline, and the second flank outline of the male rotor land outline is provided with a corresponding recess, whereby a sealing strip is provided at the crest of the male rotor land.

39. Apparatus as defined in claim 22, in which the female rotor lands are provided with addendums located outside the pitch circle of the female rotor and the male rotor grooves are provided with corresponding de-dendums inside the pitch circle of the male rotor.

40. Apparatus as defined in claim 22, in which there

are clearing spaces between the flank outlines of the male rotor and the envelopes developed by the flank outlines of the female rotor, said spaces decreasing in angular extent around the centre of the male rotor to a minimum adjacent to the pitch circle of the rotor at least on the flank outline cooperating with the second flank outline of a female rotor groove.

41. Apparatus as defined in claim 22, in which the male rotor has four lands and grooves and the female rotor has six lands and grooves, with the radial extent of the grooves of the female rotor inside the pitch circle thereof being between 18% and 21% of the outer diameter of the male rotor.

42. Apparatus as defined in claim 41, in which the radial extent of the female rotor grooves inside the pitch

circle is 18.5-20% of the outer diameter of the male rotor.

An asymmetric groove and land profile for cooperating female and male rotors in a screw rotor compressor or expander. One flank of a female rotor groove is disposed generally outside and the other flank generally outside a circular arc having its centre at the point of intersection between the pitch circle and a radial line through the innermost point of the groove, resulting in a small blow hole, negligible pockets, unidirectional thrusts on both rotors, and a large displacement volume for the size of the particular apparatus.
